UNITED STATES PATENT OFFICE.

ROBERT L. LEONARD, OF NEW YORK, N. Y., ASSIGNOR TO W. H. & A. E. MARGERISON & CO., OF PHILADELPHIA, PENNSYLVANIA, A FIRM COMPOSED OF WILLIAM H. MARGERISON AND ALBERT E. MARGERISON.

DESIGN FOR A TOWEL.

Application filed December 3, 1927. Serial No. 24,375. Term of patent 3½ years.

To all whom it may concern:

Be it known that I, ROBERT L. LEONARD, a citizen of Germany, residing at New York city, in the county of New York, and State of New York, have invented a new, original, and ornamental Design for a Towel, of which the following is a specification, reference being had to the accompanying drawing, forming part thereof.

The figure is a perspective view of a towel showing my new design.

I claim:

The ornamental design for a towel, as shown.

ROBERT L. LEONARD.
